Primary Examiner — T Chase Nelson*Assistant Examiner* — Kelly L Gross(74) *Attorney, Agent, or Firm* — Jose Cherson Weissbrot(57) **CLAIM**

The ornamental design for a foot arch support wrap, as shown and described.

DESCRIPTION

FIG. 1 is a top perspective view of a foot arch support wrap, showing my new design;

FIG. 2 is a front elevational view thereof;

FIG. 3 is a rear elevational view thereof;

FIG. 4 is a left side view thereof;

FIG. 5 is a right side view thereof; and,

FIG. 6 is a top plan view thereof.

The broken lines in the figures are for the purpose of illustrating portions of the foot arch support wrap, which form no part of the claimed design. The dot-dash broken lines represent stitching and form part of the claimed design.
